UNITED STATES PATENT OFFICE.

GILBERT F. HELSON, OF NEW YORK, N. Y., ASSIGNOR TO E. R. DURKEE & CO., OF NEW YORK, N. Y., A FIRM.

APPARATUS FOR ELEVATING AND LOWERING THE BEARINGS OF ROTATING DEVICES.

1,244,206.

Specification of Letters Patent. Patented Oct. 23, 1917.

Application filed July 29, 1916. Serial No. 112,021.

To all whom it may concern:

Be it known that I, GILBERT F. HELSON, a subject of the King of Great Britain, but having declared my intention of becoming 5 a citizen of the United States, residing at the borough of Manhattan, in the city, county, and State of New York, have invented an Improvement in Apparatus for Elevating and Lowering the Bearings of 10 Rotating Devices, of which the following is a specification.

My invention relates to an apparatus for elevating and lowering the bearings of rollers, and is particularly designed for use 15 in connection with an apparatus for pressing corks into the necks of bottles, which corks have previously been lightly inserted into the mouths of the bottles by hand as the bottles are delivered from a filling apparatus upon a conveyer band traveling 20 over a stationary table, and the object of the invention is to provide for adjusting the pressing roller to act upon corks in bottles of different heights and to hold the bearings of the rotating roller stationary when 25 so adjusted and during the pressing operation.

In the accompanying drawing:

Figure 1 is a side elevation illustrating 30 my invention, and

Fig. 2 is a plan view of the same.

Similar reference numerals indicate like parts throughout the several views. 35 10 indicates two upright side frames oppositely disposed, one on each side of a table 11. The bottoms of these frames may be secured to a flooring or base, but I prefer to fasten them to the table by screws or bolts 12 as shown. The table 11 is provided 40 with legs 13, which are preferably secured to the floor or base 14.

The side frames 10 each consist of two spaced apart upright members 15, 16 connected at the bottom by a cross-piece 17, 45 from which project spread legs 18, connected at the bottom by the cross-piece 19. These several parts of each side frame are preferably made integral, although they may be separate pieces properly secured together if desired.

The facing sides of the members 15 and 16, in each side frame are rabbeted as at 50 on their vertical edges, and between these members 15 and 16, there is a block 21, upon two opposite sides of which there is a ver-

tical groove 22, into which the reduced portion of the facing surfaces on each upright 15 and 16 formed by said rabbeting fits forming a guide for said block which is 60 slidable up and down between the said uprights. Adjacent the lower end of each block 21 there is a circular opening 23, to receive the ends of and form a bearing for a shaft 24 upon which is mounted a cylinder or roller 25 located between the two side 65 frames 10.

Upon one end of the shaft 24 there is a drive pulley 39 to which rotary movement is imparted from any suitable source.

The outer surface of the cylinder or roller 70 25 may be roughened or corrugated or covered with felt or other fibrous material, but I prefer to cover it with rubber 26, having a ribbed or corrugated outer surface.

Centrally located in the top of each block 75 21 there is a vertical hole into which is secured a bushing 27 interiorly threaded, and below said hole the center of the block is cut out leaving a vertically elongated opening 28.

29 indicates two screws, one for each block 21, one end of each of which is screwed into one of the threaded bushings 27, in said blocks.

The upper ends of these screws pass 85 through holes in the top cross plate 30, one adjacent each end, which plate is secured to the top of the uprights 15 and 16 by bolts 31, or in any other suitable manner. This cross plate 30 extends outward from 90 said uprights a predetermined distance at each side where it is provided at each end with a right angled upward projection 32, each provided with a hole through which pass the ends of a horizontal rod 33, upon 95 the projecting end of which is fastened a hand-wheel 34.

Upon the upper end of each screw 29, there is keyed a bevel gear 35, in gear with the bevel gears 36, keyed to the horizontal 100 rod 33.

37 indicates a conveyer band passing over rollers 38 (only one of which is shown). The shaft of the driving roller for the band is provided with a drive pulley to which 105 rotary movement is imparted from any suitable source.

In the top surface of the table 11, I 110 preferably form a longitudinal channel 40, within which the conveyer band 37 is re-

ceived and travels, thereby preventing any lateral displacement of said band.

The directions of rotation of the roller 38 and cylinder 25, are indicated by the arrows, and the cylinder is regulated to rotate at the same speed at which the conveyer band travels.

42 designates a chute leading from a bottle filling apparatus (not shown), and 10 down said chute the filled bottles 43 slide onto the conveyer band 37.

In the bottle filling apparatus employed by me and in connection with which I make use of my present invention, four alined 15 bottles are filled simultaneously, and afterward slide down the chute 42, in the same line, the chute being provided with four guide ways 44, 45, 46, and 47, one for each bottle, and the four bottles therefore pass 20 from the end of the chute onto the conveyer band 37 in perfect alinement or nearly so, and are drawn along toward the rotating cylinder 25, in this order.

An attendant or attendants, provided with 25 a quantity of corks are positioned at one or both sides of the delivery chute 42 and as the filled bottles 43 slide down, a cork 48 is lightly placed in the mouth of each bottle without interrupting its forward movement, 30 and when these corks come into contact with the revolving cylinder 25, they are pressed firmly down into the necks of the bottles thus securely stoppering the same.

This operation does not impede the travel 35 of the conveyer band 37 to any appreciable extent, and the stoppered bottles continue along to labeling and wrapping devices in the same order.

While I have illustrated the cylinder 25 40 as hollow and provided with spokes 49, secured to the shaft 24, it will be readily understood that the cylinder may be a solid roller provided with trunnions fitted into the bearings in the blocks 21.

45 The cylinder 25 may be positioned nearer to or farther from the top of the table 11 by turning the hand wheel 34 thereby rotating the horizontal rod 33, which by means of the beveled gears 36 and 35 will rotate the 50 screws 29 within the threaded bushings 27 in the blocks 21 thereby raising or lowering said blocks and cylinder according to which way the rod 33 is rotated, and when adjusted to the desired position the blocks and 55 roller bearings will remain stationary during the operation of the apparatus.

By the employment of my invention in connection with a bottle stoppering apparatus such as shown and described, the filled

bottles after leaving the filling apparatus 60 may be quickly, uniformly and firmly stoppered as they are passed on to labeling and wrapping devices without interruption in their travel.

I claim as my invention:

1. An apparatus of the character described, comprising two oppositely placed upright frames, a block provided with a longitudinal slot and circular opening below the same supported in each frame and slideable vertically therein, a single pressure roller, a shaft for the same journaled in said circular openings in the blocks, an interiorly threaded bushing within an opening in the top of each block and communicating with the slot therein, a screw passing through each bushing and provided with a beveled gear fixed to its upper end, a transverse plate secured to the top of each frame provided with holes for the passage of said screws, a horizontal rod supported in bearings above said plate, beveled gears secured to said rod meshing with the gears on said screws, and means attached to said rod for rotating the same whereby the roller is elevated or lowered to the desired extent, and held in true horizontal position with revolute motion only while the apparatus is operated.

2. An apparatus of the character described, comprising two oppositely placed upright frames, a block provided with a longitudinal slot and circular opening below the same supported in each frame and slideable vertically therein, a single pressure roller provided with an elastic covering, a shaft for said roller journaled in said circular openings in the blocks, an interiorly threaded bushing within an opening in the top of each block and communicating with the slot therein, a screw passing through each bushing and provided with a beveled gear fixed to its upper end, a transverse plate secured to the top of each frame provided with holes for the passage of said screws and having its ends upturned at right angles, a horizontal rod supported in bearings in said upturned ends, beveled gears secured to said rod meshing with the gears on said screws, and a hand wheel secured to the end of said rod for rotating the same, whereby the roller is elevated or lowered to the desired extent, and held in true horizontal position with revolute motion only while the apparatus is operated.

Signed by me this 24th day of July, 1916.

GILBERT F. HELSON.
